UNITED STATES PATENT OFFICE.

ALFRED BODE AND KARL BÖTTCHER, OF BENRATH, NEAR DÜSSELDORF, GERMANY.

FLOATING CRANE.

No. 863,898.

Specification of Letters Patent.

Patented Aug. 20, 1907.

Application filed June 27, 1907. Serial No. 331,147.

To all whom it may concern:

Be it known that we, ALFRED BODE and KARL BÖTTCHER, subjects of the German Emperor, and residents of Benrath, near Düsseldorf, in the Province of the 5 Rhine, German Empire, have invented certain new and useful Improvements in or Relating to Floating Cranes, of which the following is an exact specification.

In order to avoid the clumsiness of the old types of floating cranes they have recently been constructed 10 as rotary tower cranes, rotary cranes with jibs adapted to be drawn in, and so forth. In these cranes the center of rotation of the crane has always been in the middle of the pontoon.

The chief object of the present invention is to keep 15 the pontoon for rotary floating cranes as small as possible and the crane itself as light as possible. The solution of the problem is based upon the known fact that, with a rectangular pontoon, on displacing the crane laterally, a certain inclination takes place sooner than when the 20 crane or its center of gravity is displaced longitudinally. In addition to this very different kinds of work have to be performed by means of floating cranes. Thus, for example if it is a question of removing heavy goods 25 from lighters the grab hook has not to extend more than 3 to 4 meters at the most beyond the outer edge of the pontoon, while in the case of large steamers it must reach as much as 18 meters from the pontoon edge. When the grab hook is working at such a distance from the edge of the pontoon large loads are of 30 course only moved when the jib lies longitudinally of the crane, and if this latter is arranged centrally on the pontoon the total projection or overhang is so great that the crane must be made exceedingly heavy and the pontoon must consequently be made large and 35 heavy also. This is obviated in accordance with the present invention by displacing the crane from the middle of the pontoon approximately to such an extent that its distance from one of the ends of the pontoon is equal to the distance from the sides. This enables 40 a considerable reduction of the weight of the crane, and consequently of the size and weight of the pontoon, to be effected.

In order that our said invention may be clearly understood we will describe the same more fully with reference to the accompanying drawings in which:

Figure 1 is a side elevation of a floating crane constructed in accordance with our invention, and Fig. 2 is a plan of same. Figs. 3 and 4 are respectively an

elevation and a plan illustrating a modified construction.

The float or pontoon *p* is rectangular in plan. The rotatable crane frame *k* is carried by a fixed pillar which is located out of the center of the pontoon in such a way that it is equally distant from three of the edges. A jib capable of swinging in a vertical plane is arranged 55 on the frame of the crane. The drawing also shows a counterweight *g* and a vessel *s* against which the end of the pontoon is placed, while on one side of the pontoon a barge or lighter *f* is shown.

Now assuming that the pontoon is 23 meters wide 60 and 38 meters long, the lighter 6 meters wide and the ship 20 meters wide, and the grab hook has to extend as much as 17.5 meters beyond the end of the pontoon, with the usual arrangement of the crane at the middle of the pontoon the greatest length of overhang would 65 amount to $19+17.5=36.5$ meters. If, however, in accordance with the novel arrangement the crane is situated only as far from the end as from the sides, that is to say 11.5 meters, the greatest overhang is reduced by 7.5 meters and is no longer 36.5 but 29 meters. 70

The counterweight *g* serves to compensate the correspondingly greater moments arising in the longitudinal direction owing to the greater overhang required in that direction; this counterweight may be constituted by water or other convenient material, while for 75 the relatively small overhang in the transverse direction of the pontoon a counterweight will be unnecessary. The counterweight *g* is preferably arranged at such a distance from the middle of the pontoon that the crane has the same inclination when loaded to its 80 fullest extent and with the maximum distance between the grab hook and the axis of rotation as when unloaded and with its jib drawn in.

In the construction illustrated in Figs. 3 and 4, the counterweight consists of a block of concrete, masonry or other appropriate material extending to the surface of the pontoon and constituting a portion of it; it thus constitutes a platform onto which the heaviest loads may be lowered.

Having now particularly described and ascertained 90 the nature of our said invention and in what manner the same is to be performed, we declare that what we claim is:

1. In a floating crane the combination of a pontoon rectangular in plan with a rotatable crane frame carrying 95 the jib, a fixed pillar supporting said crane frame, said pil-

lar being eccentrically arranged on the pontoon in such a manner that it is equally distant from three of the edges of said pontoon and a counterweight compensating the weight of the crane substantially as and for the purpose specified.

2. In a floating crane the combination of a pontoon rectangular in plan, with a rotatable crane frame, carrying the jib, capable of swinging in a vertical plane, a fixed pillar supporting said crane frame, said pillar being eccentrically arranged on the pontoon in such a manner that it is equally distant from three of the edges of said

pontoon, a counterweight compensating the weight of the crane and forming a platform substantially as and for the purpose specified.

The foregoing specification signed at Düsseldorf this 15 first day of June, 1907.

ALFRED BODE,
KARL BÖTTCHER.

In presence of two witnesses—

M. ENGELS,
ALFRED POHLMAYER
